UNITED STATES PATENT OFFICE.

WILLIAM ZIMMER, OF BELLAIRE, OHIO.

CASTER.

SPECIFICATION forming part of Letters Patent No. 295,850, dated March 25, 1884.

Application filed November 3, 1883. (No model.)

To all whom it may concern:

Be it known that I, WILLIAM ZIMMER, of Bellaire, in the county of Belmont and State of Ohio, have invented a new and useful Improvement in Casters or Cruet-Stands; and I do hereby declare that the following is a full and exact description of the same, reference being had to the accompanying drawings, and to letters of reference marked thereon.

10 My invention relates to an improvement in casters or cruet-stands, and particularly to that class which are made of glass or earthenware.

15 The object of my invention in general is to produce a caster or cruet-stand of the simplest and cheapest character, and at the same time one that shall be neat in appearance and most convenient for use at the table. With respect to these objects it is found essential, first, to 20 make the cruet-support of such a shape and so arrange its sockets or receptacles as to enable it with its foot or feet to be pressed complete in one mold; second, to provide it with cruet sockets or receptacles so arranged as to 25 accommodate cruets with handles; and, third, to provide it with cruets so arranged that the contents of each are visible from opposite sides of the table, and any particular cruet may be reached and removed without turning the 30 caster.

To attain these results and enable the cruet-support, its sockets or receptacles, and foot or feet to be pressed complete in one mold, the invention consists in making the cruet- 35 support of a rectangular shape, or nearly so, and providing it with two or more cruet sockets or receptacles arranged in the same line adjacent to one another, and one or more upon each side of the bail, which is detachable and 40 is centrally applied to the sides of the cruet-support, said support being adapted to receive the bail and to hold it in a vertical rigid position, all as more fully hereinafter described.

For the better comprehension and understanding of my invention, and to enable those skilled in the art to know how to properly construct the same, reference should be had to the accompanying drawings, in which—

Figure 1 represents a view in perspective 45 of the caster or cruet-stand without the cruets; and Fig. 2, a similar view of a modified form

of the caster or cruet-stand, including the cruets, one of which is represented with handles arranged upon two of its sides at points diametrically opposite; and Fig. 3 is a partial detail, showing how the bail is secured in a vertical position.

A represents the cruet-support, made of glass or earthenware, and preferably rectangular in form, or nearly so. This portion A 55 of the caster is supported, as shown in Fig. 1, by four feet or legs, *a a a a*, arranged two upon each side at points equidistant apart; or, as shown in Fig. 2, this support may be supported by two feet or legs, *a a*, arranged one 60 upon each side of the center thereof, at points diametrically opposite.

It will be understood that whatever the form or arrangement of the feet may be, they are, with the cruet-support, to be pressed complete 70 in one mold.

The cruet-support A is provided with four sockets or receptacles, *b b b b*, which are arranged in the same straight line and adjacent to one another. This arrangement of the receptacles adapts them to receive cruets with or without handles, as shown in Fig. 2, while with casters having these receptacles arranged in a circle or in a manner that will bunch the cruets, as is common with the casters now in 75 use, it is impossible to use cruets with handles, for the reason that there is insufficient space for their accommodation.

B represents a spring-metal bail, whose ends are sprung into recesses or ears *c c*, formed one 80 upon each side of the support A, and centrally at opposite points, in order that the bail may not interfere with the removal of any of the cruets, which are to be arranged one or more upon each side thereof. This bail, when 85 applied to the caster, is held and maintained in a vertical rigid position by means of notches *d d*, formed upon the edge of a flange, *e*, which extends around the cruet-support A, and projects outwardly from the top thereof, as shown 90 in Fig. 1. Instead of this flange extending entirely around the cruet-support, an economical and equally an efficient substitute may be found in the projection *e* shown in Fig. 2; but for symmetry and neatness I prefer the flange 95 shown in Fig. 1.

The several parts of this caster may be or-

nameted and made of a configuration most attractive to the eye, and it will also be apparent that the same may be made of metal.

It will be understood that in casters of square or annular form, having the cruet-receptacles arranged other than in the same straight line, the inlet to the mold is too small to receive a sufficient amount of molten glass to form completely at one pressure and in the same mold the cruet-support and its foot or feet, and thus it is that these elements have heretofore been pressed in separate molds and afterward joined in well-known ways.

By making this caster or cruet-stand rectangular in form, or nearly so, and arranging the cruet-receptacles in the same straight line, an inlet results for the molten glass of a size about equal to the longitudinal and transverse diameter of the article to be produced, and therefore the capacity of this inlet is sufficient to enable the cruet-support and its foot or feet to be pressed complete in the same mold.

I do not desire to claim the bail to my caster, broadly, but confine myself to its particular combination and arrangement in my caster.

Having thus described my invention, and set forth some of its advantages, what I claim, and desire to secure by Letters Patent, is—

1. A glass or earthenware caster having two or more cruet-receptacles sunk into its base in the same straight line, and with supporting-feet, and all pressed complete in the same mold, substantially as described.

2. The combination, in a glass or earthenware caster having two or more cruet-receptacles sunk into its base in the same straight line, and supporting-feet, all pressed in the same mold, of a detachable handle sprung into opposite recesses in the lower part of the base, and retained in a vertical position by notches at the top of the base, substantially as described.

In testimony whereof I affix my signature in presence of two witnesses.

WILLIAM ZIMMER.
